UNITED STATES PATENT OFFICE

2,100,941

METHOD OF AND MACHINE FOR KNITTING FABRIC

William Coleman, Johnson City, Tenn., assignor to Scott & Williams, Incorporated, New York, N. Y., a corporation of Massachusetts

Application October 20, 1936, Serial No. 106,673

10 Claims.

(Cl. 66—24)

This invention relates to circular knitting machines and the product thereof and more particularly to circular knitting machines for knitting stockings having ribbed fabric insteps and legs and plain fabric tops and it is an object of this invention to provide a circular knitting machine having means for an improved method of operation in the transfer of the loops from the dial needles to the cylinder needles at the change from 5 rib to plain fabric. It is also an object of this invention to provide an improved stocking having a ribbed fabric instep and leg and a plain fabric top with elastic threads laid or knit therein.

In the drawings—

15 Figure 1 is a diagrammatic view showing the relative positions of the cylinder and dial needles, the cylinder needle jacks and operating cams for the cylinder needles and jacks, the various parts being positioned as during the knitting of the 20 course of ribbed fabric immediately prior to the transfer;

Figure 2 is a partial diagrammatic view similar to Figure 1, but showing the position of the parts during transfer;

25 Figure 3 is a partial diagrammatic view similar to Figure 1 but showing the position of the parts during the knitting of the plain fabric top with a rubber thread laid in;

Figure 4 is a fragmentary enlarged view showing portions of several courses of loops before, 30 during and after transfer;

Figures 5 and 6 are fragmentary enlarged views showing in elevation and plan, respectively, the relation of the loops and the cylinder and dial 35 needles during transfer;

Figures 7 and 8 are views in plan and elevation, respectively, of cams for operating the cylinder needles during the transfer and several preceding courses and the operating means for the cams;

40 Figures 9 and 10 are fragmentary views of cylinder needles used, Figure 9 showing a needle with a butt of normal size and Figure 10 showing a needle with a butt partially cut away at the bottom to delay raising the needle;

45 Figure 11 is a diagrammatic view of a stocking manufactured in accordance with this invention;

Figure 12 is a broken plan view showing the operating means for the jack operating cam for the needles engaging the elastic yarn, other parts 50 of the machine being omitted;

Figure 13 is a view in elevation of an operating cam of the operating means shown in Figure 12, and

55 Figure 14 is a fragmentary view in elevation showing the manner of controlling the operating means of Figure 12 by a push rod operated from the main pattern drum.

In the drawings the invention is shown applied to a ribbed fabric hosiery knitting machine, such 60 as is shown in the patent to Scott No. 1,641,554,

issued September 6th, 1927, and as in that machine, the stocking is knit beginning at the toe and comprises a ribbed fabric instep and leg, L and a plain fabric top W which, however, is modified by the insertion of an elastic thread R which is engaged at spaced wales in spaced courses. The transfer from the ribbed to the plain fabric takes place at T and, if desired, a different yarn may be introduced for the knitting of the top a few courses prior to the change from ribbed fabric 10 to plain fabric.

In the drawings there is shown only so much of the structure of the Scott patent referred to as is necessary to illustrate this invention. The dial needles d, preferably constructed as shown in the 15 Scott Patent No. 1,641,101, issued August 30th, 1927, are shown in Figures 1 and 2 arranged with the cylinder needles N so as to knit a 4×1 ribbed fabric. The cylinder needles have jacks under alternate needles, the needles n¹ immediately following the dial needles and the needles n³ being without jacks, while the needles n² and n⁴ are provided with jacks. The jacks are provided with long and short butts in alternation. The cylinder needles are also provided with the usual long 20 and short butts which cooperate with the knitting cams 360, 357, 361 and 7; the needles n² having their butts cut away at the bottom so that when raised, as by cam 25, they are not raised as soon 25 as or to the same extent as the needles n¹ in advance thereof. The cam 25 is made adjustable in order to time the raising of the needles with respect to the operation of the cast-off portion of the dial needles d during transfer. The dividing cam 4, the draw down cam 8 and the jack operating 30 cam 366 are also provided. In addition to these cams there is provided a jack operating cam 380 which is arranged to be inserted partially 35 so as to operate only the long butt jacks. The long butt jacks can be positioned to operate either 40 of the jack operated needles. The cam 380 is operated to engaging position by means of a spring 30 secured to the bedplate B and which engages a pin 31 fixed in the outer end of the cam carrier 32. The cam carrier 32 is slidably 45 mounted on the bedplate B and has the cam 380 secured to its inner end. A lever 33 pivotally mounted on a pin 34 secured to the bedplate B has one arm engaged with the pin 31 on the cam carrier 32 and the other arm connected by a link 50 35 to a crank 36 fixed on a shaft 37. The shaft 37 is journaled in brackets 38 secured to the bedplate B and has fixed thereon a crank 39 to which there is connected a push rod 40 which is guided by a bracket 41 secured to the bedplate B. The 55 push rod 40 is positioned to be engaged by a cam 42 fixed on a gear wheel 43 secured to a shaft 44 journaled in the machine frame A. The gear wheel 43 engages a gear 45 secured on the main drive shaft (not shown) and the ratio of the gears 60

is such that gear 43 makes one revolution for every four revolutions of the needle cylinder. The cam 42 is of such a length as to support the push rod during the period of three revolutions of the needle cylinder and to leave it unsupported during the period of one revolution and the lever arrangement is such that when the push rod 40 is supported by the cam 42 the cam 380 is held out by the lever 33 and when the push rod 40 is not supported by the cam 42 the cam carrier 32 is moved inwardly carrying the cam 380 to its operative position. This arrangement causes the cam 380 to be placed in its operative position during every fourth course but in order to prevent the cam 380 being placed in operative position when not desired the shaft 37 is provided with an arm 46 positioned to be engaged by a projection 47 on a push rod 461. The push rod is operated by a cam or cams (not shown) on the main pattern 20 drum 120 arranged to hold the push rod in elevated position at such time or times as it is desired to keep the cam 380 out of operative position continuously. In the present case, the push rod 461 will be held in raised position at all times except during the knitting of the plain fabric top at which time the push rod is in its lowered position and the position of cam 380 is controlled by cam 42 on gear wheel 43.

There is also provided a draw down cam 370 which is arranged to draw down the needles to a greater extent than usual and is slidably mounted in a guide 10 on the bed plate B. The cam 370 is provided with a projection to which is pivotally connected one end of a link 12, the other end of which link is pivotally connected to an end of a lever 14 pivotally mounted on a bracket 15 attached to the base plate B. The other end of the lever 14 projects into position to be engaged by a cam 16 attached to the push rod 460 which operates the dial transfer cam (not shown) so that the cam 370 and the dial transfer cam are operated simultaneously. The push rod 460 is operated by cam 122 on the main pattern drum 120. The cam 4 is operated through rod 20 by a push rod or lever, not shown, from a pattern drum, in the usual manner.

During the knitting of the foot and leg the operation is as shown in the patent to Scott No. 1,641,554. At a point a couple of courses prior to the transfer from ribbed to plain fabric the dividing cam 4 is inserted drawing down all the cylinder needles, but the alternate cylinder needles n^2 and n^4 being provided with jacks are raised upon the operation of the jacks by the cam 366 to pass over the leading stitch cam 360 to take and knit the body yarn in the usual manner. The remaining cylinder needles n^1 and n^3 pass below the leading stitch cam 360 and the center knitting cam 7 which is, at this time, in a raised position so that these needles do not take the yarn and knit.

Drawing down the cylinder needles n^1 immediately following the dial needles so as to keep these needles from taking and knitting the yarn in a couple of courses prior to the transfer course causes the loops knit by the dial needles to extend between the needles n^4 and n^2 , as shown in Figures 5 and 6, and as each dial needle loop tends to center itself between the cylinder needles with which it is connected the dial needle loop will be distorted and the loop previously knit by the dial needle will be stretched sidewise and held open.

At the beginning of the transfer course the cam

370 is inserted to draw down all the cylinder needles substantially as far as possible without rupturing the loops, the needles then being raised by cam 25. The butts on needles n^2 having been cut away at the bottom these needles are not raised as soon or as high as the other needles and serve to retain some tension on the dial needle loops, drawing these loops to the left so that as the needles n^1 are raised they engage in the dial needle loops of the previous course before the needles n^2 are raised far enough to release the tension on the dial needle loops. The dial transfer cam having been inserted simultaneously with the cam 370 the dial needles d are withdrawn leaving the dial needle loops on the cylinder needles n^1 immediately following the dial needles. The dividing cam 4 is withdrawn following the insertion of the cam 370. As in the transfer operation in the Scott Patent No. 1,641,554, the cam 370 and the dial transfer cam 20 are maintained in operative positions during a plurality of courses so as to insure the transfer of the dial needle loops to the cylinder needles.

Upon completion of the transfer the cam 370 and the dial transfer cam are withdrawn and the jack operating cam 380 and the needle operating cam 381 are inserted and simultaneously therewith the rubber yarn guide F² is operated to present the elastic thread R to the needles, the cam 380 being inserted only far enough to engage the long butt jacks. As only the alternate jacks have long butts these long butt jacks are beneath every fourth needle and when operated position their needles to be raised by the cam 381 to take the rubber thread at the yarn guide F². The yarn guide F² feeds the rubber thread below the latches of the raised needles so the rubber thread is held down as the cam 25 raises the remaining needles. The remaining needles when raised by the cam 25 pass in front of the rubber thread so that when the needles are operated by the stitch cams 360, 357, 361 to take and knit the body yarn the elastic thread is not knitted in but is engaged with the loops of the plain fabric at every fourth wale. The cam 380 is inserted for every fourth course and left in operative position throughout the course so that the elastic thread is engaged with the plain fabric loops in every fourth course. Where it is desired to knit in the elastic thread at the spaced needles in the courses in which it is introduced the cam 381 is not used and the needles taking the elastic thread retain it in their hooks when the needles are operated by the stitch cams to knit the elastic thread as well as the body yarn. With the introduction of the elastic thread the dial is raised to increase the spacing between the dial and cylinder to provide for the passage of the fabric containing the elastic thread. The top containing the elastic thread is knit of the desired length and the yarns then withdrawn and the fabric pressed off in the usual manner.

The fabric in the region of the transfer course is as shown in Fig. 5 in which course 1 and 2 are of rib fabric the wales 1 to 9, inclusive, beginning at the left, being knit by cylinder needles n^2 , n^1 , dial needle d , cylinder needles n^4 , n^3 , n^2 , n^1 , dial needle d , and cylinder needle n^4 respectively. Courses 3 and 4 are the courses prior to the transfer course in which the needles n^1 and n^3 in wales 2, 5 and 7 are drawn down and do not take the body yarn. While both needles n^1 and n^3 are arranged to miss the body yarn this is because the same arrangement is used in the starting up course. It is only necessary that the

- needle n^1 immediately following each dial needle be caused to miss the body yarn. In 2×1 rib, every other cylinder needle would need to miss the body yarn. Course 5 is the transfer course 5 in which the dial needle loops in wales 3 and 8 are transferred to the cylinder needles knitting wales 2 and 7, it being assumed the transfer is completed in the one course. In this transfer the cylinder needles n^1 engage in the dial needle loops of course 3 and the dial needle loops of course 4 when cast off the dial needles tend to straighten out but are held by the needle n^1 along with the dial needle loops of course 3. Courses 6 and 7 are plain fabric courses prior 10 to the introduction of the elastic thread. In the courses in which the elastic yarn is included the elastic yarn is fed under such tension that the fabric of the completed top is contracted by the elastic yarn to form continuous ribs extending 15 lengthwise of the stocking and giving the plain fabric top substantially the appearance of a ribbed fabric with the ribs thereof forming continuations of the ribs of the fabric of the stocking leg.
- 20 The particular fabric shown and described is not claimed herein as it is claimed in the divisional application Serial No. 160,182, filed Aug. 20, 1937.
- 25 I claim—
- 30 1. In a knitting machine for knitting rib and plain fabric and having dial and cylinder needles cooperating in the knitting of rib fabric, said needles having butts for operation thereof, cam means rendering inactive the cylinder needles immediately following the dial needles during the course prior to transfer from rib to plain knitting and a cam operating the cylinder needles during the transfer course prior to transfer to stretch the loops of the previously knit course, the butts 35 on the cylinder needles immediately following the inactive needles being arranged to delay the raising of said needles to hold the dial loops stretched during transfer thereof to the inactive needles.
- 40 45 2. In a knitting machine for knitting rib and plain fabric and having dial and cylinder needles cooperating in the knitting of rib fabric, cam means rendering inactive the cylinder needles immediately following the dial needles during the course prior to transfer from rib to plain knitting and cam means operating cylinder needles to stretch the dial needle loops for engagement by the inactive cylinder needles during the transfer course.
- 50 55 3. In a knitting machine for knitting rib and plain fabric and having dial and cylinder needles cooperating in the knitting of rib fabric, cam means rendering inactive the cylinder needles immediately following the dial needles during the course prior to transfer from rib to plain knitting and cam means operating the cylinder needles immediately following the inactive cylinder needles to stretch the dial needle loops for engagement by the inactive needles during the transfer course.
- 60 65 4. In a knitting machine for knitting rib and plain fabric and having dial and cylinder needles cooperating in the knitting of rib fabric, cam means rendering inactive during the course prior to transfer from rib to plain knitting the cylinder needles which take the dial needle loops, a cam operating the remaining cylinder needles during
- the transfer course to stretch the loops of the previous course prior to transfer and butts on the cylinder needles following the cylinder needles taking the dial needle loops delaying the raising of said needles to hold the dial needle loops stretched during transfer.
5. In a knitting machine for knitting rib and plain fabric and having dial and cylinder needles cooperating in the knitting of rib fabric, cam means rendering inactive during the course prior to transfer from rib to plain knitting the cylinder needles which take the dial needle loops, cam means drawing down the remaining cylinder needles during the transfer course to stretch the loops of the previous course prior to the transfer point and means operating cylinder needles so the dial needle loops are held stretched while being taken by the cylinder needles.
6. In a knitting machine for knitting rib and plain fabric and having dial and cylinder needles cooperating in the knitting of rib fabric, cam means rendering inactive the cylinder needles immediately following the dial needles during the course prior to transfer from rib to plain knitting and a cam operating the cylinder needles to stretch the loops thereon during the transfer course prior to the transfer of the dial needle loops.
7. In a knitting machine for knitting rib and plain fabric and having dial and cylinder needles cooperating in the knitting of rib fabric, said needles having butts for operation thereof, cam means rendering inactive the cylinder needles immediately following the dial needles during the course prior to transfer from rib to plain knitting and a cam operating the cylinder needles to stretch the loops thereon during the transfer course prior to the transfer of the dial needle loops, the butts on the cylinder needles following the inactive needles being arranged to delay the raising of those needles while the inactive needles engage the previously knit dial loops.
8. In a knitting machine for knitting rib and plain fabric and having dial and cylinder needles cooperating in the knitting of rib fabric, cam means rendering inactive during the course prior to transfer from rib to plain knitting the cylinder needles which take the dial needle loops and cam means operating cylinder needles to hold the dial needle loops stretched while being taken by the cylinder needles during the transfer course.
9. In a method of changing from the knitting of ribbed fabric to the knitting of plain fabric in a dial and cylinder machine, the steps of rendering inactive the cylinder needles immediately succeeding the dial needles, drawing down all cylinder needles to stretch the loops of the previous course, delaying the raising of the needles immediately succeeding the inactive needles while the inactive needles take dial needle loops and casting off the loops from the dial needles.
10. In a method of changing from the knitting of ribbed fabric to the knitting of plain fabric in a dial and cylinder machine, the steps of drawing down all cylinder needles to stretch the loops of the previous course, delaying the raising of the needles immediately following the needles taking the dial loops while the dial loops are taken and casting off the loops from the dial needles.

WILLIAM COLEMAN.
